UNITED STATES PATENT OFFICE.

TRUMAN G. PALMER, OF CHICAGO, ILLINOIS.

CURRENT-MOTOR.

No. 825,154.

Specification of Letters Patent.

Patented July 3, 1906.

Application filed August 5, 1903. Serial No. 168,260.

To all whom it may concern:

Be it known that I, TRUMAN G. PALMER, a citizen of the United States, and a resident of Chicago, in the county of Cook and State 5 of Illinois, have invented certain new and useful Improvements in Current-Motors, of which the following is a full, clear, and exact description.

The invention relates more particularly to 10 that class of current-motors in which the force of a running stream of water is exerted upon a plurality of blades or paddles that are successively immersed into and lifted from the stream.

15 The invention has for its object to improve this class of current-motors in various particulars; and with this object in view the invention consists in the features of novelty 20 hereinafter described, illustrated in the accompanying drawings, and particularly pointed out in the claims at the end of this specification.

Figure 1 is a view in central vertical section through a current-motor embodying my 25 invention. Fig. 2 is a view in horizontal section on line 2 2 of Fig. 1. Fig. 3 is a view in vertical cross-section on line 3 3 of Fig. 1. Fig. 4 is a detail side view of one end of the motor.

30 In many situations my improved motor will be supported upon a catamaran or other suitable buoyant structure; but as this forms no part of the present invention I have not deemed it necessary to illustrate it in the accompanying drawings.

35 As shown, the frame A of the motor is made of iron or steel channel-bars, as by such bars the frame can be made exceedingly strong and without great weight. The top 40 and bottom side bars a and a' of the main frame are shown as connected at and between their ends by posts a², between which extend the top and bottom cross-bars a³. In suitable bearings at the ends of the main 45 frame A are journaled the shafts B and B', to each end of which are fixed the sprocket-wheels B² and B³. Over these sprocket-wheels pass the endless chains C, that carry 50 paddles or blades D in suitable number. As shown, each of the paddles or blades D is pivotally mounted upon a transverse rod E, that extends between and is secured to sprocket-chains C, and preferably the ends of each of the rods E are extended beyond

the sprocket-chains and are fitted with anti-friction-rollers e, that move within the channels of the guide-bars F and F'. The guide-bars F and F' are secured to the inner sides of the main frame A and preferably extend from end to end of the main frame at points opposite the top and bottom of the sprocket-wheels B² and B³. Preferably the channels of the guide-bars F and F' are slightly flaring, (the antifriction-rollers e being correspondingly shaped,) so as to prevent the lodgment of sediment within the channels of the guide-bars.

The paddles or blades D are preferably formed from sheet metal, and in the preferred form of my invention that edge of each of the 70 blades or paddles that travels lowermost in the water is weighted, so as to aid in causing each paddle to assume its proper position as it enters the stream. A simple manner of weighting the ends of the paddles is by reverting a 75 sheet-metal flange d at the edge of the paddle over a metal bar d' at such point. In order to cause the paddles D to more effectively assume their proper positions, I prefer also to pivotally support each of the paddles at one side of 80 its plane, this being readily effected by forming each paddle with flanges d² at its ends, through which the rods E will loosely pass.

To cause the paddles D to properly enter and leave the water, I employ the improved 85 arrangement of guys or cables next to be described.

To each paddle, at points adjacent that edge that travels uppermost when the paddle is submerged and which for convenience will be 90 hereinafter termed the "light" edge of the paddle, are connected at each side the cables G and G', the opposite ends of these cables extending, respectively, forwardly and rearwardly from the paddle and being connected, 95 preferably, by swivel-eyes g (see Fig. 3) to the rods E of the adjacent front and rear paddles. The connection of the guys or cables G and G' to the paddles may be conveniently effected by providing holes in the end flanges 100 of the paddles to which the ends of the cables will be fastened.

By reference to Fig. 1 of the drawings the action of the guys or cables G and G' will be 105 readily understood. As each paddle in its uppermost or idle position moves toward the front of the machine it occupies a substantially vertical position; but as the pivot-rod

of the preceding paddle passes on to and around the front sprocket-wheels B^2 the guys or cables G of said next succeeding paddle gradually slacken, thereby permitting the 5 weighted edge of said next succeeding paddle as it approaches the sprocket-wheels to drop forwardly and downwardly until when it is above the sprocket-wheels it assumes the position of the paddle, as shown in Fig. 1 of 10 the drawings; but at this time the guy or cable G' still remains taut, thus exerting its control over the light edge of the paddle, so that the paddle is caused to gradually assume a forwardly and downwardly inclined position 15, the degree of inclination being controlled by the cables G' . Hence it will be seen by reference to Fig. 1 that as each paddle passes downward and into the water it is positively guided and enters the water without 20 any splash and is so held that there is no danger of any jarring or racking of the machine because of the sudden strain exerted on the paddle by the current, and the paddle thus entering the water does not present 25 itself at right angles to the current until the paddle is submerged. As a paddle passes downwardly from the horizontal plane of the front sprocket-wheels B^2 and rearwardly from such sprocket-wheels the sprocket- 30 chains straighten out, and this serves to increase the distance from the edge of the paddle to the points on the sprocket-chains—i. e., the pivot-rods E —where the stay-cables are attached, thus gradually bringing each 35 paddle after it has left the front sprocket-wheel into an upright position without any jar or jerk, and in such upright position the paddle will receive the full impact of the current. The paddle thus continues to travel in up- 40 right position until the pivot-rod of the preceding paddle passes onto and partially around the rear sprocket-wheels B^3 , when as the distance between the light edge of the paddle that has not yet passed onto the 45 sprocket-wheels and the pivot-rod of the preceding paddle that is on the sprocket-wheels is lessened the paddle as it approaches the rear sprocket-wheels can turn about its axis, thereby permitting its weighted lower end to 50 swing with the current. Hence it will be seen that as the paddles rise from the water they occupy an inclined position which prevents their lifting the water and by so much avoids the usual back pressure or resistance 55 to the travel of the paddles. As the pivot-rod of each paddle passes around the rear sprocket-wheels B^3 the guys or cables G remaining taut cause the light edges of the paddle to swing forwardly and downwardly, as indicated by the adjacent arrow, Fig. 1, until the position of each paddle is reversed, each 60 paddle being thus gradually revolved as it passes around the machine.

While I prefer to use wire rope for the guys

or cables G and G' , I do not wish the invention to be understood as restricted to the use of rope, since any other suitable kind of guys may be employed in place thereof.

In order to prevent the guys or cables from contacting with the sprocket-chains, I prefer to employ guards or fenders H at the ends of the paddles, these guards or fenders extending between the guys or cables G and G' and the sprocket-chains and being preferably attached to the ends of the paddles by angular brackets h (see Fig. 3) and setting loosely over the pivot-rods E . These fenders H may be semicircular plates of open-work material or may be solid plates of sheet metal, as preferred.

In order to insure the forward and downward turning of each paddle as it passes over the front sprocket-wheel B^2 , I prefer to provide a guide device that shall cause the downward tipping of the weighted edges of the 85 paddles at such point. Preferably this guide consists of a curved spring-bar K , that is supported by a bar k , extending between side bars a^5 , that are secured to the end posts a^2 of the main frame A . The spring-bar K is 90 curved upwardly and forwardly, so that as the paddles approach the front sprocket-wheels B^2 the light edges of the paddles will come into contact with the spring-bar or guide K , and as they ride over this bar the 95 weighted edges of the paddles will be tipped forwardly and downwardly against the tension of the guys or cables G' . Hence the proper delivery of the weighted edges of the paddles to the current of water is at all times 100 insured.

As the paddles leave the water at the rear end of the motor the guys or cables become relaxed, and to prevent any tendency of a paddle in passing around the rear sprocket-wheels B^3 to turn suddenly about its axis as it leaves the water I prefer to provide one or more curved guide-bars M , against which the light edge of the paddle may contact as the weighted edge leaves the water. The guide-bar M is preferably of spring metal and has its inner end secured to a transverse bar m , that is supported between the side bars a^5 of the main frame. It will thus be seen that as each paddle leaves the water at the rear of 115 the motor any tendency toward excess movement about its axis will be checked by the guide-bar M , along which the light edge of the paddle will travel. As each paddle passes over the rear sprocket-wheels B^3 in 120 forward direction the guys or cables become taut and bring the paddles to the vertical position shown in the drawings; but to avoid any jarring or racking of the machine as the paddles assume this position I prefer to employ a check bar or spring P , the downwardly and forwardly inclined portion of which extends slightly into the path of travel of the 125

paddles, as clearly shown in Fig. 1 of the drawings. Hence it will be seen that as each paddle in passing from the rear sprocket-wheels is brought to vertical position by the 5 tightening of the cables its weighted edge may contact with the check bar or spring P, that will relieve the paddle from any sudden jerk or jar that might tend to rattle or injure the machine. The check-bar P is preferably 10 of spring metal and has its upper end fixed to the cross-bar a^3 of the main frame. From the foregoing description it will be seen that as the paddles travel around their sprocket-wheels they are delivered to and withdrawn 15 from the water in most effective positions and are so guided that the jars and strains upon the machine are reduced to a minimum.

In order to most effectively deliver the current of water to the several paddles of the 20 motor so that the thrust upon the paddles shall in a measure be equalized, I have provided the improved construction of wings or deflectors next to be described.

At various points along each side of the 25 main frame A are attached the wings or deflectors R, which in the preferred form of the invention are of varying lengths. Preferably each of the wings R is mounted upon a vertical rod r, the lower end of which is pivotally 30 sustained in a bracket r' upon the adjacent bottom side bar a' of the main frame, while its upper end is pivotally supported in the supplemental side bar a^5 , that extends from end to end of the machine at a point 35 slightly above the water-level. As each wing R is thus pivotally supported at its inner end, it will be seen that the wings may be turned at any desired angle to the water-current. By forming the wings R of varying lengths 40 the current of water can be most effectively directed to the several blades or paddles that are submerged. In order to enable the wings R to be conveniently shifted, I prefer to attach to each wing adjacent to its outer end a 45 cable S, that passes around a pulley S', carried by a bracket s, projecting outwardly from the adjacent guide-bar F' of the machine, the free end of the cable S extending upward and being suitably fastened to the 50 bar a^5 above the water-line or in any other convenient point of the main frame. It will be understood, of course, that the force of the 55 water-current tends to hold the wings or deflectors R in extended position; but by means of the cables S the wings can be drawn in and set at any desired angle.

I wish it understood that the details of construction above set out may be varied by the skilled mechanic without departing from 60 the spirit of the invention and that features of the invention may be employed without its adoption as an entirety. It will be understood also that the power will be taken from the shaft or shafts of the sprocket-

wheels by suitable gearing; but as this forms 65 no part of the present invention I have not deemed it necessary to illustrate such gearing in the drawings.

Having thus described my invention, what I claim as new, and desire to secure by Letters Patent, is—

1. In a current-motor, the combination with suitable paddle-supporting means, of a plurality of paddles each pivoted intermediate between its top and bottom edges, an excess of weight being on that side of each paddle that travels lowermost in the water, and means engaging the lighter sides of the paddles and serving to control the tilting movement of said paddles as their heavier ends enter the water.

2. In a current-motor, the combination with suitable paddle-supporting means, of a plurality of paddles each pivoted intermediate between its top and bottom edges, an excess of weight being on that side of each paddle that travels lowermost in the water and cables connected to the lighter sides of the paddles and serving to restrict the turning movement of the paddles as their heavier ends enter the water.

3. In a current-motor, the combination with suitable paddle-supporting means, of a plurality of pivoted paddles and guys or cables extending in opposite directions from 95 said paddles and whereby the movement of said paddles is controlled.

4. In a current-motor, the combination with suitable paddle-supporting means, of a plurality of pivoted paddles and guys or cables extending in opposite directions from 100 said paddles and swivel connections for said guys or cables.

5. In a current-motor, the combination with a suitable paddle-supporting means, of 105 a plurality of pivoted paddles, rods whereon said paddles are sustained and guys or cables extending in opposite directions from said paddles at the same sides of their pivotal points, the ends of the guys or cables that lead 110 from one paddle being connected to the pivot-rods of the adjacent paddles.

6. In a current-motor, the combination with endless sprocket-chains and with 115 sprocket-wheels for said chains at opposite ends of the motor-frame, of a plurality of paddles pivotally connected to said sprocket-chains and guys or cables leading in opposite directions from each paddle at one side of its 120 pivotal point.

7. In a current-motor, the combination with suitable paddle-supporting means, of a plurality of paddles each pivoted intermediate between its top and bottom edges, an excess of weight being on that side of each 125 paddle that travels lowermost in the water and means for controlling the tilting movement of said paddles comprising guys or ca-

bles connected to the lighter sides of said paddles and guides arranged to engage said paddles to turn them about their pivotal points under control of said guys or cables.

5 8. In a current-motor, the combination with endless sprocket-chains and with sprocket-wheels for said chains at opposite ends of the motor-frame, of a plurality of paddles pivotally connected to said sprocket-chains, guys or cables attached to said paddles at one side of their pivotal points and guides adjacent said sprocket-wheels and extending into position to engage the paddles and turn them about their pivotal points.

15 9. In a current-motor, the combination with suitable paddle-supporting means, of a plurality of pivoted paddles, guys or cables attached to said paddles at one side of their pivotal points and a guide adjacent the front 20 of the machine and arranged to engage said paddles to turn them about their pivots under control of said guys or cables toward the current as the paddles enter the water.

10. In a current-motor, the combination 25 with sprocket-chains and with sprocket-wheels for said chains at opposite ends of the motor-frame, of a plurality of paddles pivotally connected with said sprocket-chains, a guide located intermediate between the 30 sprocket-chains and extending in position to engage the paddles and turn them downward toward the current as said paddles pass forwardly and downwardly over the front sprocket-wheels and guys or cables connect- 35 ed to said paddles to limit their movement.

11. In a current-motor, the combination with sprocket-chains and with sprocket-wheels for supporting said chains at the opposite ends of a motor-frame, of a plurality of 40 paddles pivotally connected to said sprocket-chains, a guide at the rear end of the main frame for engaging each paddle at one side of its pivotal point as it leaves the water and guys or cables connected to the paddles for 45 controlling their movement.

12. In a current-motor, the combination with sprocket-chains and with sprocket-

wheels at opposite ends of the motor-frame for supporting said chains, of a plurality of paddles pivotally connected with said 50 sprocket-chains and a guide located above the sprocket-chains at the rear end of the machine, said guide extending in position to contact with the uppermost edges of the paddles after they have been withdrawn from 55 the water.

13. In a current-motor, the combination with sprocket-chains and with sprocket-wheels at opposite ends of the motor-frame for sustaining said sprocket-chains, of a plurality of paddles pivotally connected with 60 said sprocket-chains, guys or cables extending in opposite directions from said paddles and suitably connected with the sprocket-chains, and a guide at the rear end of the main 65 frame for engaging each paddle to insure its gradual change of position.

14. In a current-motor, the combination with suitable paddle-supporting means, of a plurality of paddles, guys or cables connected 70 to said paddles for controlling their movements and guards or fenders at the opposite ends of the several paddles.

15. In a current-motor, the combination with suitable paddle-supporting means, of a 75 plurality of paddles, guys or cables connected to said paddles for controlling their movements and guards or fenders at the opposite ends of the several paddles, said guards or fenders being connected to and revoluble 80 with the paddles.

16. In a current-motor, the combination with suitable paddle-supporting means, of a plurality of paddles pivoted thereto intermediate their edges, guys or cables connected to 85 said supporting means and to the sides of the paddles that are uppermost in the water, and means for turning said paddles about their pivots under control of said guys or cables as the paddles enter the water.
